UNITED STATES PATENT OFFICE.

ROBERT FARIES, OF DECATUR, ILLINOIS.

SPRING-MOTOR.

SPECIFICATION forming part of Letters Patent No. 404,526, dated June 4, 1889.

Application filed June 6, 1888. Serial No. 276,177. (No model.)

To all whom it may concern:

Be it known that I, ROBERT FARIES, a citizen of the United States, residing at Decatur, in the county of Macon and State of Illinois, 5 have invented certain new and useful Improvements in Spring-Motors; and I do hereby declare the following to be a full, clear, and exact description of the invention, such as will enable others skilled in the art to which 10 it appertains to make and use the same.

My motor is especially designed to rotate devices for displaying goods; and the novelty exists in the speed-regulator and the general arrangement of parts, as hereinafter set forth. 15 In the drawings accompanying and forming a part of this specification, Figure 1 represents the working parts of my device. Fig. 2 is a face view of the main gear-wheel, showing the main shaft in section with the 20 drive-ratchet mounted thereon; and Fig. 3 is an elevation of the incased works, with the spring indicated by dotted lines and the upper portion of the casing partly broken away to show the load-supporting shaft and to indicate by dotted lines its connection with the 25 drive-shaft of the motor.

The bed-plate A has lateral extensions B, that are provided with threaded leveling-bolts b. It also has lugs D, that are provided 30 with holes d, through which securing-screws d' extend, as shown in Fig. 3. The frame C provides bearings for the several parts of the motor, and the screws C'', passing through the foot-like extensions C', secure the frame to 35 the bed-plate. The casing A' rests on the bed-plate and incases the works. The central tubular upward extension A'' provides at its top a bearing for the load-supporting shaft y. The main shaft E has the spur-wheel E', 40 the spring F, and the ratchet-wheel v rigidly attached thereto. The spur-wheel G is mounted loosely on the main shaft, and is recessed in one face to receive the ratchet-wheel. The drum e and hook e' provide a 45 point of attachment for a duplicate spring in case more power is needed. Wheel G conveys motion to pinion H' on horizontal shaft H. Crown-wheel H'' on the same shaft conveys motion to a pinion on vertical drive-shaft 50 I, and said drive-shaft has a bearing in the top of frame A at c, and is preferably provided with the conical depression i. Shaft y is preferably provided with a conical lower termination adapted to the conical depression 55 in the drive-shaft, and it extends sufficiently

high to insure stable equilibrium to the encircling weight that it is designed to carry.

An obvious modification of the conical frictional connection of the vertical shafts will exist in opposing plane surfaces, and, if 60 desired, the load may receive motion from shaft y by a frictional connection, the same as specified. The pressure of shaft y on shaft I will develop sufficient friction to cause the load to revolve, and a temporary stoppage or 65 reversal of the direction of the load's rotation by external force will not injuriously affect the motor. Sleeve t screws into the casing and provides a bearing for winding-crank u, which is provided on its inner end with a 70 drive-pinion s, that meshes with wheel E', as shown in Fig. 1. The spring is wound by the crank, and its force is exerted on the primary wheel through pawls w, which are held in contact with the ratchet by springs x. 75

The governor or speed-regulator comprises the wheel I' on shaft I, meshing with a pinion on shaft K, the wheel K' on shaft K, meshing with pinion r on shaft q, cross-head p on shaft q, rods n, suspended from the cross-head and 80 weighted at n', and the annular band M loosely embracing the rods. Plate L provides bearings for shaft K and q, and plate L' furnishes a bearing for the lower end of shaft q. As the head rotates, the rods are 85 swung outward at their lower ends by centrifugal force, and after a certain speed is developed press against the band and develop friction in a degree exactly proportionate to the surplus power to be neutralized. 90

I claim as new and desire to secure by Letters Patent—

1. A motor-regulator comprising the shaft q, carrying cross-head p, rods n, suspended vertically from the cross-head, and annular 95 band M, encircling the rods below their points of suspension, as set forth.

2. A motor-regulator comprising the shaft q, carrying cross-head p, rods n, suspended vertically from the cross-head and having 100 weights n', and annular band M, encircling the rods below their points of suspension, as set forth.

In testimony whereof I affix my signature in presence of two witnesses.

ROBERT FARIES.
